CHILD'S ROCKING CHAIR

Radcliffe W. Hunter, 533 E. 33rd Place, Chicago, Ill., and
Stephen E. Konecnik, 1135 Broadway, Park Ridge, Ill.

Filed Aug. 22, 1961, Ser. No. 66,459

Term of patent 14 years

(Cl. D15—1)

FIG. 1

FIG. 3

FIG. 2

FIGURE 1 is a front perspective view of a child's rocking chair, showing our design;

FIGURE 2 is a side elevational view thereof, the view from the opposite side being identical; and

FIGURE 3 is a rear elevational view on a reduced scale.

We claim:

The ornamental design for a child's rocking chair, as shown.
